UNITED STATES PATENT OFFICE.

CHARLES HENRY SCHIOPBACH, OF AURORA, ILLINOIS, ASSIGNOR TO SIMON FLORSHEIM AND NORMAN S. FLORSHEIM, OF CHICAGO, ILLINOIS.

DESIGN FOR A CORSET.

SPECIFICATION forming part of Design No. 32,629, dated May 1, 1900.

Application filed December 29, 1899. Serial No. 742,001. Term of patent 7 years.

To all whom it may concern:

Be it known that I, CHARLES HENRY SCHIOPBACH, a citizen of the United States, residing at Aurora, in the county of Kane and State of Illinois, have invented and produced a new and useful Design for Corsets, of which the following is a specification, reference being had to the accompanying drawing, forming a part hereof.

- Said drawing is a perspective view of a corset embodying my design.

The leading or characteristic feature of my design consists of a plurality of ornamental circumferential bands or girdles, each of which has marginal raised parts separated by a central space and a distinctive intermediate central longitudinal stripe filling said space between said marginal raised parts, said bands extending around the corset, combined with bands or strips arranged vertically and extending from top to bottom of the corset, intersecting and extending over said circumferential bands or girdles. The girdles on

each lateral half of the corset extend from the front to the rear edge thereof and are spaced at intervals from the lower to the upper margins of the corset. The girdles occupying the upper part of each lateral half of the corset are curved upwardly at their ends, while those occupying the lower part of each lateral half of the corset are curved downwardly at their ends. The vertical transverse bands overlie said girdles and are spaced at substantially uniform intervals around the corset, the said bands being spread apart or arranged to diverge upwardly and downwardly above and below the central smaller part of the corset.

I claim as my invention—

The design for a corset substantially as herein shown and described.

Dated this 22d day of December, A. D. 1899.

CHARLES HENRY SCHIOPBACH.

In presence of—

W. H. PEASE,
JOHN C. WEILAND.
